J. Franklin Myers
ATTORNEY

UNITED STATES PATENT OFFICE.

HENRY HERMANI, OF BALTIMORE, MARYLAND, ASSIGNOR TO THE TIN DECORATING COMPANY OF BALTIMORE, OF BALTIMORE, MARYLAND, A CORPORATION OF NEW JERSEY.

KEY FOR KEY-OPENING CANS.

Application filed July 20, 1927. Serial No. 207,262.

This invention is an improvement in keys for key opening cans, and in methods for holding the key in place on the cover of the can prior to use in removing the rip strip connecting the cover to the can body.

In cans provided with rip strips, it is usual to provide a key for removing the rip strip when opening the can. Such keys have heretofore been connected with the can by spot welding to the cover, or by providing independent holding means, such as a hasp or the like beneath which the key is held.

Either method is objectionable in that the key is outside the overall dimensions of the can and is liable to be dislodged, or in the former instance the key is liable to be held so tightly as to present difficulty in removal.

One of the primary objects of the present invention is to provide a construction of key, capable of being deformed into a condition of smaller outline than its normal state, and resilient to return to such normal state when released, whereby the key may be fitted into a recess and will be held therein by its own resiliency.

Another object is the provision of a key and a holding means therefor, so constructed and arranged that the key and its holding means will be within the overall dimensions of the can and out of position to be engaged by foreign bodies which might tend to dislodge the same.

Another object is the provision of a key of simple inexpensive construction.

With these and other objects in view the invention consists in the construction and novel combination of parts fully described hereinafter, illustrated in the accompanying drawings, and pointed out in the claims appended hereto, it being understood that various changes in the form, proportion, size and minor details of construction within the scope of the claims, may be resorted to without departing from the spirit of the invention.

In the drawings:

Fig. 1 is a side view of a rip strip can having parts broken away to show the key.

Fig. 2 is a plan view of the can with the key in place.

Figs. 3 to 11 inclusive are plan views of alternate constructions of key.

The present embodiment of the invention is shown in connection with a can composed of a body 1 of usual construction, and a cover 2, which is connected to the can by a rip strip 3, having a projecting tongue 4, to be engaged by the slot of the opening key to remove the strip.

In the present construction the body of the can cover 2 is provided with a central circular depression or recess 5 having walls parallel with the axis of the can cover, and the key is adapted to be arranged within this recess, the recess being of a depth to hold the key inside the overall dimensions of the can and below the level of the cover body, as clearly shown in Fig. 1.

In all of the constructions the key is formed from a strip of resilient metal bent to shape, the strip being in effect a flattened wire and each construction includes a handle portion and a shank having a slot for engagement by the tongue.

The embodiment of key shown in Fig. 2 comprises a shank portion 6 having the tongue engaging slot 7, and a handle portion 8, which in the present instance is substantially S-shaped. The relative dimensions of the key and recess 5 are such that the key will engage within the recess, the shank extending substantially diametrically thereof, when the handle portion is contracted, so that the outline of the key is smaller than normal.

The contraction in the present instance is enabled by the movement of the parts of the S-shaped handle toward each other and toward the shank, and both extremities of the key engage the side wall of the recess as clearly shown. In Fig. 3, the key comprises a shank 9 and a handle portion 10, the handle portion being S-shaped like that shown in Fig. 2. The shank is similar to the shank of the key 6-7, but instead of being slotted, the extremity 11 of the shank is bent back parallel with the body and in spaced parallel relation, to provide a tongue engaging slot 12. The only difference between the said key and that of Fig. 2 is in the provision for the slot.

In Fig. 4 the key is formed by doubling the strip upon itself to provide the shank, the extremity of the strip being bent outwardly at substantially right angle from the

shank to the handle portion. The similar portions 13—13^a of the strip forming the shank are spaced apart from each other to provide the slot 14 for the rip strip tongue, 5 while the ends of the strip 15—15^a cooperating to form the handle portion are in substantial alinement. The provision of the slot 14 also enables the key to be contracted, by moving the elements 15—15^a toward each 10 other. Further contraction is enabled by movement of the portions 15—15^a toward the shank. In the present instance the extremities of the strip engage the recess wall.

The Fig. 5 construction is similar to that 15 of Fig. 4 consisting of the shank 16—16^a and the handle portion 17—17^a. The extremities of the strip are however bent laterally with respect to the portions 17—17^a away from the portions 16—16^a, as indicated at 18 and 18^a. A better grip is thus provided on the handle portion, but the construction is otherwise the same as that of Fig. 4.

In Fig. 6 the strip is doubled to form 20 the shank 19, substantially the same as the shank 13—13^a of Fig. 4. The extremities of the strip are bent laterally outward to form the handle 20—20^a, and the portions 20—20^a form an acute angle with the shank 30 19. The extremity of each portion 20—20^a is bent slightly away from the shank so that the handle portions present a concave edge away from the shank. The doubling of the strip to form the shank provides for the 35 tongue engaging slot in the same manner as the constructions of Figs. 4 and 5. The arrangement in Fig. 6 provides for a slightly better grip, and for somewhat more resiliency than the Fig. 4 construction and the 40 extremities of the strip in the Fig. 6 construction engage the wall of the recess.

In Fig. 7 the strip is doubled upon itself 45 to form the shank 21, and the extremities are reversely curved as shown at 22 to provide the handle portion. This arrangement provides increased resiliency and enables a better grip on the handle portion. In Fig. 50 8 the strip is doubled to form the shank 23, and the handle portions 24 are formed by reversely bending the ends of the strip as in Fig. 7. In this construction, however, the extremities 25 of the strip lie on the outer sides of the reversely bent portions from the shank, extending toward each other at 55 substantially a right angle, thus increasing the area of the handle portion, and also the resiliency of the key. The resiliency is also increased by providing an eye 26 at the end of the shank remote from the handle portion. In each of the constructions shown in 60 Figures 4 to 8 inclusive the extremities of the strip bear against the recess wall when the key is in place.

In Fig. 9 the key is formed by doubling 65 the strip to form the shank 27. The handle

portion 28 is in the form of a ring or eye. The extremities of the strip are adjacent, as clearly shown, but are spaced slightly away from each other to enable contraction of the ring when inserting the key in the recess. 70

In Fig. 10 the shank 29 is formed in the same manner as in the Fig. 7 construction, but the handle portion 30 is S-shaped, thus enabling contraction in the same manner as in the Figs. 2 and 3 constructions. In Fig. 75 11 the shank 31 is formed in the same manner, and the handle is a diamond shaped frame 32. The extremities of the strip are adjacent, but are spaced apart in the same manner as the Fig. 9 construction to enable 80 contraction of the key.

In use, after the can is completed, a key is inserted in the recess, by slightly contracting the same so that it will fit therein, with the shank extending substantially diametrical to the recess. The expansion of the key causes it to grip the recess wall closely, holding the key against accidental displacement, but allowing the easy removal 85 thereof when desired for use. 90

In all of the constructions except that of Fig. 2 the tongue engaging slot is formed by the doubling of the material, so that only the bending operation is necessary in the formation of the key. It will be understood that the plane of the improved key in each instance is in the plane of the strip. 95

It will be apparent from a consideration of the drawing that the key is so shaped that when inserted in the depression it will engage the wall thereof at a plurality of points, and will provide resiliency in the handle portion to enable shortening of the distance between the points without lateral bending of the shank. In Figs. 4 to 8 inclusive and Fig. 10, the key engages at 100 three points while in Figs. 2, 3, 9 and 10, the engagement is at two points, namely the end of the shank and a part of the handle 105 in alinement therewith. 110

In Figs. 3 to 11 inclusive the arrangement is such that the slot for receiving the rip strip tongue is formed between parts of material lying along side each other, thus to enable the formation of the key without the necessity for punching a slot. In all of the constructions the resiliency which enables shortening of the distance between engaging points, whereby to enable insertion of the key in the depression is in the handle 115 portion, and there is no lateral bending of the shank during insertion or removal. 120

What is claimed as new is:—

1. In combination, a rip strip can, and a key for operating the strip to open the can, the can having in the cover thereof a depression with the side wall thereof straight and perpendicular to the plane of the cover, and the key of a shape to be received within the depression with substantially opposite 130

relatively minute portions thereof engaging the recess wall and with a resilient portion between said portions.

2. In combination, a rip strip can, and a key for operating the strip to open the can, the can having in the cover thereof a depression, and the key of a size to fit within the depression and formed from a resilient piece so bent that the key engages the de-

pression wall at substantially opposite 10 points, said walls being straight and perpendicular to the plane of the cover, so that the key is held in the depression by the engagement of said points with the depression wall.

15

Signed at Baltimore, State of Maryland, this 18th day of July, A. D. 1927.

HENRY HERMANI.
